UNITED STATES PATENT OFFICE.

WILLIAM ZOERB, OF DEDHAM, MASSACHUSETTS.

DESIGN FOR AN EYEGLASS OR SPECTACLE CASE.

SPECIFICATION forming part of Design No. 29,220, dated August 16, 1898.

Application filed June 13, 1898. Serial No. 683,369. Term of patent 14 years.

To all whom it may concern:

Be it known that I, WILLIAM ZOERB, a citizen of the United States, residing at Dedham, in the county of Norfolk and State of Massachusetts, have invented and produced a new and original Design for an Eyeglass or Spectacle Case, of which the following is a specification, reference being had to the accompanying drawings, forming a part thereof.

Figure 1 shows a top view of my newly-designed eyeglass-case; Fig. 2, an under side view of the same, and Fig. 3 an end view of the same.

The leading feature of my design consists in a narrow portion along one edge of one of the oblong lids of the case, at or about midway its length, which is uncovered or left exposed by the other lid and thus appears as

a lip, and a tab on the exterior of the other lid.

²⁰
a b represents the two oblong lids.

a' represents a lip which appears on one edge of the lid *a* at or about midway its length.

b' represents a tab on the exterior of the ²⁵ lid *b* near one edge and opposite the lip *a'*.

I claim—

The design for an eyeglass or spectacle case herein shown and described.

In testimony whereof I have signed my ³⁰ name to this specification in the presence of two subscribing witnesses.

WILLIAM ZOERB.

Witnesses:

B. J. NOYES,

JENNIE L. HUTCHINSON.
